US00D619732S

(12) **United States Design Patent**
Mugge et al.

(10) **Patent No.:** US D619,732 S
(45) **Date of Patent:** ** Jul. 13, 2010

(54) **MOLDED SURFACE OF A CONCRETE PRODUCT**

(75) Inventors: **Jimmie L. Mugge**, Inver Grove Heights, MN (US); **Jay J. Johnson**, Star Prairie, WI (US)

(73) Assignee: **Anchor Wall Systems, Inc.**, Minnetonka, MN (US)

(**) Term: **14 Years**

(21) Appl. No.: **29/312,875**

(22) Filed: **Nov. 18, 2008**

(51) **LOC (9) Cl.** 25-01

(52) **U.S. Cl.** D25/113

(58) **Field of Classification Search** D25/102,

(57) **CLAIM**

The ornamental design for molded surface of a concrete product, as shown and described.

DESCRIPTION

FIG. 1 is a front view of an embodiment of a concrete product, according to our new design, the portions shown in broken lines forming no part of the design sought to be patented;

FIG. 2 is a right side view of the concrete product of FIG. 1, the portions shown in broken lines forming no part of the design sought to be patented;

FIG. 3 is a left side view of the concrete product of FIG. 1, the portions shown in broken lines forming no part of the design sought to be patented;

FIG. 4 is a top view of the concrete product of FIG. 1, the portions shown in broken lines forming no part of the design sought to be patented;

FIG. 5 is a bottom view of the concrete product of FIG. 1, the portions shown in broken lines forming no part of the design sought to be patented; and,

FIG. 6 is a perspective view of the concrete product of FIG. 1, the portions shown in broken lines forming no part of the design sought to be patented.
